UNITED STATES PATENT OFFICE

150,577

DESIGN FOR AN EYEGLASS CASE

Aaron Karp, New York, N. Y.

Application January 25, 1947, Serial No. 136,426

Term of patent 3½ years

(Cl. D57—1)

To all whom it may concern:

Be it known that I, Aaron Karp, a citizen of the United States of America, residing in New York city, county of Kings, and State of New York, have invented a new, original, and ornamental Design for an Eyeglass Case, of which the following is a specification, reference being had to the accompanying drawing, forming part thereof, wherein,

I claim:

The ornamental design for an eyeglass case, substantially as shown.

AARON KARP.
